UNITED STATES PATENT OFFICE.

HARRY EDUARD HOENIG, OF EAST LIVERPOOL, OHIO, ASSIGNOR OF ONE-HALF TO
JOSIAH T. SMITH, OF EAST LIVERPOOL, OHIO.

FASTENING DEVICE.

1,354,396.

Specification of Letters Patent. Patented Sept. 28, 1920.

Application filed October 20, 1915. Serial No. 56,984.

To all whom it may concern:

Be it known that I, HARRY EDUARD HOENIG, a citizen of the United States, residing at East Liverpool, in the county of Columbiana and State of Ohio, have invented new and useful Improvements in Fastening Devices, of which the following is a specification.

This invention relates to improvements in fastening devices and has particular application to a fastening device for use in conjunction with multiple two-part insulators, cleats, etc.

In carrying out the present invention, it is my purpose to provide a fastening device of the class described whereby the insulator, cleat or the like may be rigidly and securely fastened to the support and whereby the parts of the insulator, cleat or other article will be held in proper relative positions previous to the fastening of the insulator or cleat to the support, thereby eliminating the necessity for assembling the insulator or cleat while applying the same to the support.

It is also my purpose to provide a fastening device of the class described which will embrace the desired features of simplicity, efficiency and durability, which will operate efficiently and effectively for its intended purpose under all conditions and which may be manufactured and marketed at small cost.

With the above and other objects in view, the invention consists in the construction, combination and arrangement of parts hereinafter set forth in and falling within the scope of the claims.

In the accompanying drawing:

Figure 1 is a vertical sectional view through a two-part insulator equipped with a fastening device constructed in accordance with the present invention.

Fig. 2 is a cross sectional view through the fastening device.

Fig. 3 is a vertical sectional view through an insulator equipped with a modified form of the invention.

Fig. 4 is a cross sectional view through the fastening device.

Referring now to the drawing in detail, 1 designates a two-part insulator composed of porcelain, hard rubber or any other material and having the sections thereof formed with alining bores to receive the fastening device. My improved fastening de-

vice is indicated at 2 and, in the present instance, is in the form of a screw which is passed through the alining bores in the sections or the parts of the insulator. At a point adjacent to its threaded end the screw 60 is stamped or formed to provide radially extending diametrically opposed wings 3. These wings coöperate with the head of the screw to hold the sections of the insulator on the screw, as clearly illustrated in Fig. 65 1 of the drawings, and when the insulator is being applied to the support, it will be noted that the screw may be driven into the support with the sections of the insulator held thereon in proper relative positions so 70 that as the screw is turned home, the wires between the sections of the insulator will be clamped simultaneously with the securing of the insulator to the support.

In the modified construction illustrated in 75 Figs. 3 and 4, I have shown a nail in contradistinction to a screw and the nail is formed in the same manner as the screw and acts to hold the parts of the insulator properly positioned when the insulator is being 80 secured to the support.

It will be seen that my improved fastening device performs the dual function of a securing means for fastening the insulator to the support and of a holding means for 85 maintaining the parts of the insulator in proper relative positions during the application of the insulator to the support, the fastening device serving to draw the parts of the insulator into clamping engagement 90 with the wires when such fastening device is being driven home.

While I have herein shown and described certain preferred forms of my invention by way of illustration, I wish it to be understood that I do not limit or confine myself to the precise details of construction herein described and delineated, as modification and variation may be made within the scope 95 of the claims without departing from the 100 spirit of the invention.

I claim:

1. In combination in an insulator, base and cap portions having perforations extending therethrough, and a metal fastening 105 member comprising a shank extending through the perforations and provided at the end carrying the cap with an integral head which will not pass through the perforations in the cap and provided at the 110

other end with a point, the said shank being provided with a struck-up portion positioned so as to engage the base and prevent the withdrawal of the fastening member 5 therefrom.

2. An insulator comprising cap and base portions formed with perforations, and a nail extending through said perforations and having a head at one extremity and 10 means adjacent the other extremity to positively retain the cap and base on the nail and permit a substantial movement of the two along the nail.

3. An insulator comprising cap and base 15 portions formed with perforations, and a nail extending through said perforations and having a head at one extremity and means adjacent the other extremity to positively retain the cap and base on the nail and permit a substantial movement of the two along 20 the nail, the said means offering practically no resistance to the entrance of the nail into a support.

4. The combination with a holding element, of a fastener passing loosely through the same and formed with a terminal point penetrable into a support, the fastener having spaced positive stops permanently assembling it and the holding element and at 25 the same time permitting a substantial movement of the holding element longitudinally of the fastener.

5. The combination with a holding element, of a fastener passing loosely through the same and formed with a terminal point penetrable into a support, the fastener having positive stops disposed on opposite sides of said holding element, the stops serving to 30 permanently assemble the holding element and fastener and being spaced apart a sufficient distance to permit a substantial movement of the holding element longitudinally 35 of the fastener.

6. The combination with a holding element, of a fastener passing loosely through 45 the same and formed at one extremity with a head and at the other extremity with a point penetrable into a support, the fastener being provided adjacent the pointed extremity with a positive stop coöperating with the head to 50 permanently assemble it and the holding element and permit a substantial movement of the holding element longitudinally of the fastener.

7. The combination with a holding element, of a fastener passing loosely through the same and formed at one extremity with a head and adjacent the other extremity with a positive stop coöperating with the head to 55 permanently assemble the holding element and fastener, the head and stop being spaced apart a sufficient distance to permit a substantial movement of the holding element longitudinally of fastener, the latter having a terminal point penetrable into a support, 60 the stop offering substantially no resistance to the forcing of the fastener into the support.

8. The combination with a holding element, of a fastener passing slidably through 70 the same and formed at one extremity with a head and adjacent the other extremity with struck-up wings, the head and wings being disposed respectively on opposite sides of the holding element and spaced apart a 75 sufficient distance to permit a substantial movement of the holding element longitudinally of the fastener.

In testimony whereof I affix my signature in presence of two witnesses.

HARRY EDUARD HOENIG.
